ROTARY TAKE-UP FOR SEWING MACHINES

David A. Graesser, Westfield, N. J., assignor to
The Singer Manufacturing Company, Elizabeth, N. J., a corporation of New Jersey

Application May 12, 1948, Serial No. 26,525

12 Claims. (Cl. 112—248)

1

This invention is concerned with rotary take-up mechanisms for sewing machines. It represents an improvement in dynamically balanced rotary take-ups wherein a single thread-engaging element is cycled in a non-circular orbit at non-uniform angular speeds, thereby to satisfy the thread requirements of a high-speed rotary hook and reciprocating needle without the assistance of supplemental moving thread-engaging elements.

Prior successful attempts to utilize dynamically balanced, rotary take-up motions in lieu of the more conventional, unbalanced reciprocating-link type have resulted in the use of a plurality of revolving thread-engaging elements which cooperate to answer the thread-handling demands of high speed lock-stitch formation. In this invention, however, a single, revolving thread-engaging element provides the requisite thread-handling movements. More specifically, this take-up comprises a means for compounding two uniform, simple rotary motions to yield a single, resultant rotary take-up motion, the orbit of which is non-uniform in its radial displacement, but which is nevertheless dynamically balanced and well suited for high-speed thread-control.

Another feature of the invention is the non-winding characteristic of the revolving thread-engaging element. This is accomplished by rotating the thread-engaging element in a direction opposite to that rotation which is caused by the orbital movement thereof. Thus as the thread-engaging element is revolved and rotated through its orbit, it is also counter-rotated about its center-line in the opposite angular direction, thereby to "unwind" itself as fast as it "winds." The result is zero absolute rotational movement of the thread-engaging element throughout its revolutionary or orbital movement, thus precluding the possibility of unnatural winding of the needle-thread upon the thread-engaging element.

Still another feature of the invention is a timing adjusting mechanism whereby the orbit of the take-up may be shifted relatively to the stitch-forming components of the sewing machine. For example, the point at which the needle-bar is disposed at the bottom of its stroke, or the point at which the needle-thread is pulled between the thread-carrier of the hook and the thread-carrier rotation-restraining finger prior to the setting of the stitch in the work each corresponds to a preestablished point or range of points in the orbital path of the take-up element. By means of the timing adjustment, the thread-

2

handling characteristics of the take-up at those points may be altered by displacing the orbit angularly relatively to the stitch-forming components of the sewing machine.

5 Other advantages and features of the take-up will become apparent by referring to the drawings of a preferred embodiment of the invention in which:

Fig. 1 is a longitudinal sectional view of a sewing machine in which the new take-up mechanism has been incorporated.

Fig. 2 is an end elevational view of the sewing machine, showing the thread-engaging element of the take-up mechanism in full lines and a portion of the unexposed driving elements in broken lines.

Fig. 3 is an enlarged sectional view of the take-up mechanism taken substantially along the line 3—3 of Fig. 2.

20 Fig. 4 is an exploded perspective of the component elements of the take-up.

Figs. 5 to 9, inclusive, are diagrammatic views of the head-end of the sewing machine showing five positions of the thread-engaging element of the take-up and the corresponding positions of the rotary hook and needle-bar during one complete stitch forming cycle.

Fig. 10 is a graphical illustration of the unicursal, epitrochoidal path traced by the single thread-engaging element of the take-up in the formation of one stitch, and showing the five points on the curve corresponding to the positions of the sewing machine elements shown in Figs. 5—9.

35 Fig. 11 is a perspective view of the thread-carrier rotation-restraining bar.

The illustrated sewing machine comprises a frame including a bed-portion 20 supporting a vertical standard 21 which carries a horizontal bracket-arm 22. Rotatably journaled in the bracket-arm is an arm-shaft 23 which is externally actuated through a belt driven balance-wheel 24 and which reciprocates a needle-bar 25 by means of a crank 26 and connecting link 27.

40 An eye-pointed needle 25' is secured to the depending end of the needle-bar 25. Slidably journaled in the head adjacent the needle-bar is a spring-depressed presser-bar 28 having a presser-foot 29 affixed to its depending end.

45 The arm-shaft 23 also drives a vertically disposed rotary shaft 30, through a pair of bevel gears 31. The vertical shaft 30 in turn drives a horizontal rotary hook-shaft 32 through a pair of bevel gears 33, the hook-shaft 32 being disposed at the under side of the bed 20. The two

pairs of bevel gears 31 and 33 combine to step up the speed of the hook-shaft to a 2:1 ratio with respect to the arm-shaft. A rotary-hook 34 including a bobbin-case or thread-carrier 34' is secured to the end of the hook-shaft 32 and cooperates with the needle 25' in the formation of lock-stitches. The rotary hook 34 is provided with a loop-seizing beak 80 and a loop-controlling tail 81. The thread-carrier 34' of the hook is provided with a notch 83 for accommodating a finger 85 of a rotation-restraining bar 84 mounted on the under side of the bed 20. The finger 85 is fitted loosely in the notch 83 to permit the needle-thread to be passed through the notch once in the formation of each lock-stitch.

A feed-advance eccentric 35 and a feed-lift eccentric 36 are also carried by the arm-shaft 23. Surrounding the respective eccentrics are vertically disposed pitman links 37 and 38 which oscillate rock-shafts 39 and 40 within the bed-portion 20 of the sewing machine. Rock-arms 41 and 42 (Fig. 2) are secured to the rock-shafts 39 and 40 respectively and impart the usual four-motion feeding movements to a feed-bar 43 to which is affixed a feed-dog 44.

Take-up mechanism

Disposed in the head-end of the bracket-arm is the rotary take-up mechanism comprising a single, moving thread-engaging element 45. The take-up is driven by a rotary shaft 46 which is actuated by the arm-shaft 23 through a pair of gears 47 having a 1:1 speed ratio. The shaft 46 is journaled in a pair of bearings, one comprising an elongated bearing-bushing 48 secured rigidly to the frame of the sewing machine, and the other comprising a short bearing-bushing 49 which is mounted in the frame of the sewing machine for limited turning adjustment. This adjustment is controlled by a vertically disposed adjusting-finger 50 (Fig. 4) which extends upwardly to the top of the head where it joins a curved plate 51 which is releasably locked to the frame of the sewing machine by a screw 52. The adjusting-finger 50 which is rigidly affixed to the bearing-bushing 49, may be swung through a limited angular distance governed by the length of a slot 53 in the curved plate 51. The movement is utilized to effect timing changes in the take-up motion in a manner which is described later in this specification under the heading "Timing adjustment of take-up."

Rigidly affixed to the adjustable bearing-bushing 49 is a sun gear 54 provided with a concentric aperture 55 by means of which the gear is fitted over an extended hub-portion 56 formed integrally with the bearing-bushing 49. The sun gear 54 is rigidly affixed to the face of the bearing-bushing 49 and is not free to rotate with the shaft 46.

To the end of the shaft 46 is secured a disk 57, as by brazing. The disk is provided with a bearing 58 adjacent its periphery in which is rotatably journaled a short shaft or hub-portion 59 formed integrally with a planetary gear 60. The disk 57 thus functions as a planet-arm for the planetary gear 60. The sun gear 54 and planetary gear 60 are of equal diameters so that one complete rotation of the arm-shaft 23 causes the planetary gear 60 to cycle or revolve once about the sun gear 54 and also to rotate twice about its own axis in the same angular direction. The rotary motion of the gear 60 about its own axis is ultimately counteracted or nullified by mechanism hereinafter described.

The hub-portion 59 of the planetary gear 60 is provided with a concentric aperture 61 in which is fitted a shaft 62 carrying a counterbalanced pinion-arm 63. A nut 62' is threaded on the shaft 62 on the opposite side of gear 60 to secure the pinion-arm 63 thereto, and a key 64 and slot 65 prevent relative rotation therebetween. A second shaft or bearing-pin 66 projects outwardly from the pinion-arm 63, and over the pin is fitted the apertured hub or bearing-sleeve 67 of a pinion gear 68.

An internal gear 69 is rigidly seated in a channel 82 in the face of the disk 57 by means of a screw 69'. The pinion gear 68, which meshes with the internal gear 69, has a pitch diameter equal to one half of that of the internal gear. Thus the pinion gear 68 is caused to rotate twice about its own axis as it cycles or revolves once around in the internal gear. This rotation counters the rotary motion of the planetary gear 60, and establishes zero net rotation in the thread-engaging element 45 in a manner more fully discussed under an ensuing sub-heading "Non-winding mechanism." A circular plate or disk 70 is rigidly affixed to the pinion-arm 63 by means of screws 70' and a pair of mounting pins 71, and the apertured hub of the pinion gear 68 projects through a hole 72 in the face of the disk 70. The thread-engaging element 45 is provided with a mounting stud 73 which frictionally engages the apertured hub 67 of the pinion gear 68. A large, circular cover-plate 74 is affixed to the disk 57 by means of screws 74', the cover-plate being cut-out to accommodate the small disk 70.

Thread-handling movement of take-up

The orbit traced by the thread-engaging element 45 is a uni-cusped epitrochoid (Fig. 10). The generating elements for the curve are the sun gear 54 and the planetary gear 60, the latter rolling about the periphery of the former and both having equal pitch-diameters. The thread-engaging element 45 is carried by the rolling or planetary gear 60. The radial position of the thread-engaging element relatively to the periphery of the planetary gear governs the specific character or shape of the orbit. For example, if the center-line of the thread-engaging element were disposed on the pitch-diameter of the rolling gear, a cardioid curve would be generated. In the instant case, however, the center-line of the thread-engaging element is disposed inside the pitch-diameter, and the orbit consequently differs from a cardioid in that the cusp-portion "a" (Fig. 10) is flattened and the maximum radial distance of the thread-engaging element from the center of its orbit, occurring at the point "c," is decreased.

The take-up is threaded by passing the thread 75 from a thread-guide 76 through a tension device 77 over a check-spring 78, under a slack-thread controller 79, up to the thread-engaging element 45 of the take-up, and then down to the needle 25'.

The timing of the epitrochoidal orbit of the thread-engaging element relatively to the rotary hook 34 is shown in Figs. 5-10 in which Fig. 5 is the point at which the needle-bar is disposed at the bottom of its stroke; Fig. 6 is the cast-off point, or the point at which the thread-loop, after having been carried half-way around the body of the hook is about to be lifted by the action of the take-up from the loop-seizing beak 80 onto the loop-controlling tail 81 of the hook; Fig. 7 is the point

at which the thread is being pulled across the rotation restraining notch 83 in the bobbin-case carrier 34' prior to stitch setting; Fig. 8 is a point of completion of stitch setting; and Fig. 9 is the point at which the eye of the needle is re-entering the work to form the next stitch. A detailed description of the process of lock-stitch formation by means of a rotary hook referring particularly to the point at which the thread is being pulled across the rotation-restraining notch in the bobbin-case may be seen in the U. S. patent of C. A. Kessler, No. 2,085,699, dated June 29, 1937.

The points on the orbit (Fig. 10) of the thread-engaging element indicated by letters, *a*, *b*, *c*, *d* and *e*, correspond to the points in the stitch-forming cycle shown in Figs. 5, 6, 7, 8 and 9, respectively. At the point "*a*" the thread-engaging element has reached its point of minimum angular velocity, or the cusp portion of the trochoidal orbit, and vectors v_1 and v_2 , representing the two velocities which combine to produce the resultant motion of the thread-engaging element, are opposed. The two vectors being almost equal at this point there is a dwell in the take-up motion corresponding to the point at which the needle-bar has reached the bottom of its stroke. Within the next few degrees of rotation of the arm-shaft, the needle-bar begins its ascending stroke, slackening the thread which the needle has carried to the under side of the work and thereby forming a loop which is seized by the beak of the hook.

Approaching the point "*b*" the vectors v_1 and v_2 of the take-up combine to develop a resultant motion downwardly toward the hook, giving away thread thereto and permitting the thread loop to be expanded about the hook body. At the point "*b*" the loop about the body of the hook has been expanded to its maximum size prior to being pulled from the beak of the hook up onto the tail of the hook. This point in the stitch-forming cycle is called "cast-off."

Moving to the point "*c*," the vectors v_1 and v_2 are both directed upwardly away from the hook to establish the point of maximum absolute velocity of the thread-engaging element. The thread loop about the body of the hook has been rapidly contracted until one of its limbs is worked through the rotation-restraining notch 83 in the bobbin case carrier 34'. It should also be noted that at the point "*c*" the vector v_2 , which varies in magnitude throughout the take-up cycle, has attained its maximum magnitude.

Moving to the point "*d*," the thread-engaging element continues its upward movement, ultimately pulling the thread loop which has just passed about the body of the hook completely clear thereof and then drawing the freed loop, along with the bobbin thread ensnared therein, against the under surface of the work. This is called stitch-setting.

From "*d*" to "*e*" the sum of the vectors yields a steadily decreasing resultant motion in a counterclockwise direction. In this distance the take-up gives up sufficient thread to permit the check-spring 78 to return to its inoperative position and to permit the eye of the needle to carry the thread into the work. From "*e*" to "*a*" the take-up gives thread to the needle to permit the latter to move to the bottom of its stroke prior to the formation of a new stitch.

From the preceding description, it should be seen that the two vector motions v_1 and v_2 are so timed that they produce a series of constantly

varying resultant motions in the single thread-engaging element which enables the take-up to answer precisely the thread requirements of the rotary hook and reciprocating needle without the assistance of supplemental, moving thread-engaging elements, and without producing periods in its thread handling cycle in which there exists uncontrolled slack thread.

Timing adjustment of take-up

As indicated in the general description of the take-up mechanism there has been provided a means whereby the timing of the thread-handling movement may be adjusted relatively to the other stitch-forming instrumentalities.

The adjusting finger 50 (Figs. 3 and 4) is connected to the sun gear 54 through the bearing bushing 49, the latter element being free to turn a limited amount in the frame of the sewing machine. By swinging the adjusting finger within the limits governed by the length of the slot 53 in the plate 51 the sun gear may be rotated or turned about its axis independently of the shaft 46. This rotation of the sun gear rotates the planetary gear 60 a corresponding amount. The planetary gear, however, does not roll about the periphery of the sun gear during this adjustment as it does in the normal operation of the take-up, but rather turns about a fixed axis. The rotation of the planetary gear carries the thread engaging element either forwardly or backwardly along the line of its orbital motion, with the corresponding positions of the rotary hook 34 and needle-bar 25 remaining unchanged. Thus, for example, the velocity of the thread-engaging element at the time the needle thread is being worked through the rotation-restraining notch in the bobbin-case carrier may be varied.

Non-winding mechanism

There has been added to this take-up mechanism, as another important feature of the invention, a means for preventing the possibility of winding of the needle-thread upon the thread-engaging element.

The orbital movement of the thread-engaging element is composed of two simple rotary motions established by the sun and planet motion of the gear 60 rolling about the periphery of the gear 54. The thread-engaging element which is carried by the rolling gear is consequently rotated about its center line twice for each orbital revolution or take-up cycle. To compensate for this rotary movement which makes unnatural winding of the needle-thread about the thread-engaging element possible, it is preferred to counter-rotate the thread-engaging element twice during each cycle. This counter-rotation is accomplished by means of the internal gear 69 and its meshing pinion gear 68. The internal gear is eccentrically fixed upon the revolving disk 57 coaxially with respect to the planetary gear 60 and the rotary movement of the planetary gear is used to drive the pinion gear around the internal gear; the pinion-arm 63 being the connecting element therebetween. It follows that because the ratio of the pitch diameter of the internal gear to that of the pinion gear is 2:1 the pinion gear will be rotated twice during each take-up cycle. This rotation is passed on to the thread-engaging element to counter or equalize the rotary motion of the thread-engaging element which is inherent in sun and planet movement.

Having thus set forth the nature of the invention, what I claim herein is:

1. In a sewing machine, a reciprocatory thread-carrying needle, a rotary hook complementary to said needle in the formation of lock-stitches, means for rotating said hook a plurality of times for each reciprocation of said needle, take-up mechanism comprising a single thread-engaging take-up element satisfying stitch-formation thread handling requirements, and driving connections including a rotary shaft for revolving said take-up element about the center of rotation of said shaft at a varying radius of revolution and in timed relation with said hook to dispose said take-up element at its point of minimum radius of revolution at substantially the time said needle is disposed at the point of reversal of its stroke direction next prior to seizure of the needle-thread loop by said hook.

2. In a sewing machine, a reciprocatory thread-carrying needle, a rotary hook complementary to said needle in the formation of lock-stitches, means for rotating said hook a plurality of times for each reciprocation of said needle, take-up mechanism comprising a single thread-engaging take-up element satisfying stitch-formation thread handling requirements, and driving connections including a rotary shaft for cycling said take-up element in an orbital path at a constantly varying angular velocity about the center of rotation of said shaft and in timed relation with said hook to dispose said take-up element at its point of minimum angular velocity in said orbit at substantially the time said needle is disposed at the point of reversal of its stroke direction next prior to seizure of the needle-thread loop by said hook.

3. In a sewing machine, a reciprocatory thread-carrying needle, a rotary hook complementary to said needle in the formation of lock-stitches, means for rotating said hook a plurality of times for each reciprocation of said needle, take-up mechanism comprising a single thread-engaging take-up element satisfying stitch-formation thread-handling requirements, and driving connections including a fixed rotary shaft for revolving said take-up element in an orbital path about the center of rotation of said shaft at a constantly varying radius of revolution and angular velocity, said orbital movement being in timed relation with said hook to dispose said take-up element at its point of minimum radius of revolution and minimum angular velocity at substantially the time said needle is disposed at the point of reversal of its stroke direction next prior to seizure of the needle-thread loop by said hook.

4. In a sewing machine, stitch-forming mechanism including, a reciprocatory thread-carrying needle, a rotary hook having a needle-thread loop seizing element, a thread-carrier journaled in said hook, a stationary rotation-restraining finger acting to restrict the rotation of said thread-carrier, means for rotating said hook a plurality of times for each reciprocation of the needle, said rotary loop-seizing element cooperating with said needle in the formation of lock-stitches by seizing thread-loops cast out from the needle and passing the loops about said thread-carrier, rotary take-up mechanism comprising a single thread-engaging take-up element satisfying the stitch-formation thread handling requirements of said rotary hook and said needle, and driving connections including a rotary shaft for revolving the take-up element about the center of rotation of said shaft at a varying

radius of revolution and in timed relationship with said hook to dispose said take-up element at its point of maximum radius of revolution at substantially the time the thread-loop from said needle is passing between the thread-carrier and the rotation-restraining finger in the formation of each stitch.

5. In a sewing machine having a frame, a rotary take-up unit comprising a first shaft mounted in said frame for revolutionary movement about a fixed axis which is parallel to and laterally spaced from the center-line of said first shaft, a second shaft parallel to and laterally spaced from said first shaft, said second shaft being mounted for rotational movement about its own center-line and revolutionary movement about the center-line of said first shaft, driving mechanism for revolving said first shaft, driving mechanism for revolving said second shaft about said first shaft, driving mechanism for rotating said second shaft about its own center-line in an angular direction countering that of the revolution of the second shaft about the first, and a thread-engaging element carried by said second shaft.

6. In a sewing machine having a frame, a rotary take-up unit comprising a first shaft mounted in said frame for revolutionary movement about a fixed axis of revolution which is parallel to and laterally spaced from the center-line of said first shaft, a second shaft parallel to and laterally spaced from said first shaft, said second shaft being mounted for rotational movement about its own center-line and revolutionary movement about the center-line of said first shaft, driving mechanism for revolving said first shaft, driving mechanism for simultaneously revolving said second shaft about said first shaft, driving mechanism for simultaneously rotating the second shaft about its own center-line in an angular direction countering that of the revolutionary movement of the first shaft, and a thread-engaging element carried by said second shaft.

7. In a sewing machine having a frame, a rotary take-up unit comprising a rotary shaft journaled in said frame, a bearing-bushing for said shaft carried by said frame, a sun gear mounted on said bushing, a planet-arm carried by said rotary shaft, a planetary gear rotatably journaled in said planet-arm eccentrically of said shaft to mesh with said sun gear, an internal gear carried by said planet-arm and concentrically disposed with respect to said planetary gear, a pinion-arm carried by said planetary gear, a pinion gear mounted on said pinion-arm eccentrically of said planetary gear to mesh with said internal gear, and a thread-engaging element carried by said pinion gear.

8. In a sewing machine having a frame, a rotary take-up unit comprising a rotary shaft journaled in said frame, a sun gear supported by said frame, a planetary gear carried by said shaft to mesh with and roll about the periphery of said sun gear, an internal gear carried by said shaft and disposed concentrically with respect to said planetary gear, a pinion gear carried by said planetary gear eccentrically disposed relatively thereto and meshing with said internal gear, and a thread-engaging element carried by said pinion gear.

9. In a sewing machine having a frame, a rotary take-up unit comprising a thread-engaging element mounted on said frame to partake simultaneously of simple revolutionary move-

ments about two centers spaced from each other and spaced from the center-line of said thread-engaging element, and driving connections for rotating the thread-engaging element about its own center-line in an angular direction countering at least one of its simple revolutionary movements.

10. In a lock-stitch sewing machine having a frame carrying stitch-forming instrumentalities including a reciprocating needle and a rotary hook, the improvement which consists in a rotary take-up for satisfying the thread requirements of the rotary hook, said take-up comprising a rotary shaft, a bearing-bushing for said shaft mounted in said frame for limited turning movement, an adjusting arm secured to said bushing for turning the bushing in the frame, releasable locking mechanism for fixing the angular position of said bushing relatively to said frame, a sun gear carried by said bushing, a planetary gear carried by said shaft eccentrically thereof to mesh with and roll about said sun gear, and a thread-engaging element carried by the planetary gear.

11. In a lock-stitch sewing machine having a frame carrying stitch-forming instrumentalities driven in timed relationship including a reciprocating needle and a rotary hook, the improvement which consists in a rotary take-up for satisfying the thread requirements of the needle and rotary hook, said take-up comprising a sun gear mounted in the frame for selective angular displacement relatively thereto, locking mechanism for fixing the selected position of said sun gear relatively to said frame, a planetary gear mounted in said frame to mesh with

said sun gear and to partake of combination rotary and revolutionary movement in rolling about the periphery thereof, and a thread-engaging element carried by said planetary gear.

- 5 12. In a lock-stitch sewing machine having a frame carrying stitch-forming instrumentalities including a reciprocating needle and a rotary hook, the improvement which consists in a rotary take-up for satisfying the thread requirements 10 of the needle and rotary hook, said take-up comprising a rotary shaft, a bearing-bushing for said shaft mounted in said frame for limited angular displacement, an adjusting arm secured to said bushing for angularly displacing the 15 bushing in the frame, a releasable locking means for fixing the angular position of said bushing relatively to said frame, a sun gear carried by said bushing concentrically with respect to said shaft, a planetary gear carried by said shaft eccentrically thereof to mesh with and roll about the periphery of said sun gear, an internal gear carried by said shaft and disposed concentrically with respect to said planetary gear, a pinion gear carried by said planetary gear eccentrically 20 thereof and meshing with said internal gear, and a thread-engaging take-up element carried by said pinion gear.
